US00D570179S

(12) **United States Design Patent** (10) **Patent No.:** **US D570,179 S**
Byers (45) **Date of Patent:** **** Jun. 3, 2008**

(54) **HAND-HELD SHARPENER DEVICE**

(75) Inventor: **Gary L Byers**, Columbia Falls, MT
(US)

(73) Assignee: **Locan Properties, LLC**, Kalispell, MT
(US)

(**) Term: **14 Years**

(21) Appl. No.: **29/260,148**

(22) Filed: **May 19, 2006**

(51) **LOC (8) Cl.** **08-05**

(52) **U.S. Cl.** **D8/93**

(58) **Field of Classification Search** **D8/90, D8/91, 92, 93; 76/82, 82.2, 84, 86, 88; 451/540, 451/552, 557, 558, 559**

See application file for complete search history.

Primary Examiner—Philip S. Hyder

(74) *Attorney, Agent, or Firm*—Carl G. Dowrey

(57) **CLAIM**

The ornamental design for a hand-held sharpener device, as shown.

DESCRIPTION

FIG. 1 is a perspective view of the hand-held sharpener device;

FIG. 2 is a right side elevational view of the hand-held sharpener device;

FIG. 3 is a left side elevational view of the hand-held sharpener device;

FIG. 4 is a front elevational view of the hand-held sharpener device;

FIG. 5 is a rear elevational view of the hand-held sharpener device;

FIG. 6 is a top plan view of the hand-held sharpener device;

FIG. 7 is a bottom plan view of the hand-held sharpener device;

FIG. 8 is a perspective view of a modified embodiment of the hand-held sharpener device;

FIG. 9 is a right side elevational view of the hand-held sharpener device;

FIG. 10 is a left side elevational view of the hand-held sharpener device;

FIG. 11 is a front elevational view of the hand-held sharpener device;

FIG. 12 is a rear elevational view of the hand-held sharpener device;

FIG. 13 is a top plan view of the hand-held sharpener device; and,

FIG. 14 is a bottom plan view of the hand-held sharpener device.
